UNITED STATES PATENT OFFICE

128,633

DESIGN FOR A COMBINED SHIRT AND COLLAR PROTECTOR

Stephen Lighter, Milwaukee, Wis.

Application April 7, 1941, Serial No. 100,200

Term of patent 14 years

To all whom it may concern:

Be it known that I, Stephen Lighter, a citizen of the United States, residing at Milwaukee, in the county of Milwaukee and State of Wisconsin, have invented a new, original, and ornamental Design for a Combined Shirt and Collar Protector, of which the following is a description, reference being had to the accompanying drawing, forming part thereof.

In the drawing:

Fig. 1 is a top plan view of the combined shirt and collar protector, showing my new design in its unfolded position; and

Fig. 2 is a perspective view of the article in its folded position.

I claim:

The ornamental design for a combined shirt and collar protector, substantially as shown.

STEPHEN LIGHTER.
